UNITED STATES PATENT OFFICE.

WILLIAM CHAPMAN HORNER, OF INDIANAPOLIS, INDIANA, ASSIGNOR TO WESTERN CLOCK COMPANY, OF LA SALLE, ILLINOIS, A CORPORATION OF ILLINOIS.

DESIGN FOR A CLOCK-FRAME.

47,695.

Specification for Design.

Patented Aug. 10, 1915.

Application filed May 13, 1915. Serial No. 27,940. Term of patent 7 years.

To all whom it may concern:

Be it known that I, WILLIAM CHAPMAN HORNER, a citizen of the United States, residing at 2146 Broadway, Indianapolis, in the county of Marion and State of Indiana, have invented a new, original, and ornamental Design for Clock-Frames, of which the following is a specification, reference being had to the accompanying drawing, forming part thereof.

The figure is the front view of a clock frame, showing my new design.

I claim:

The ornamental design for a clock frame as shown.

WILLIAM CHAPMAN HORNER.

Witnesses:

LOUISE BENNETT,
JOSEPHINE GASPER.
